UNITED STATES PATENT OFFICE.

WILLIAM F. HELMOND, OF HARTFORD, CONNECTICUT, ASSIGNOR TO UNDERWOOD
TYPEWRITER COMPANY, OF NEW YORK, N. Y., A CORPORATION OF DELAWARE.

TYPEWRITING MACHINE.

Original application filed June 13, 1919, Serial No. 303,913. Divided and this application filed April 5, 1920. Serial No. 371,312.

To all whom it may concern:

Be it known that I, WILLIAM F. HELMOND, a citizen of the United States, residing in Hartford, in the county of Hartford and 5 State of Connecticut, have invented certain new and useful Improvements in Typewriting Machines, of which the following is a specification.

This invention relates to the means where-
10 by the type-keys effect letter-feeding move-
ments of the carriages of typewriting ma-
chines. In this application, which is a di-
vision of my prior application, Serial No.
303,913, filed June 13, 1919, (now Patent No.
1411,024, dated March 28, 1922), the inven-
15 tion disclosed and claimed relates more par-
ticularly to an improved construction and
mounting of the universal bar which trans-
mits the movements of the keys to the letter-
feeding dogs; and to improvements in means
20 whereby the type-bars of the machine may
be inserted and removed. The claims of the
aforesaid parent application are confined to
other parts of the typewriter escapement
25 mechanism, including improvements in the
means for controlling the movements of the
feed-dogs and the means for mounting the
escapement wheel.

The universal bar in the Underwood type-
30 writing machine is curved or segmental, is
operated directly by the type-bars, and forms
part of a frame which at its rear end is
carried upon a rocking frame. This uni-
versal bar not only operates the escapement
35 dogs, but also vibrates the ribbon up in
front of the platen at the type-strokes, and,
owing to the narrowness of the printing
field of the ribbon, particularly when a bi-
chrome ribbon is used, it is necessary for the
40 vibrator to be accurate in its movements. To
this end, it is necessary for the universal bar
to be accurately placed with reference to the
type-bars, and it has therefore been the
45 practice to bend and twist the universal bar
frame in attempting to secure the desired ac-
curate relationship of the universal bar with
the type-bars. It is necessary that the active
50 face of the universal bar, that is, the face
which is engaged by the type-bars, shall be
in a plane which is parallel with the general
plane of the type-bar pivots. An object of
the invention is to provide simple and effi-
cient means for securing this result. This

object is accomplished by mounting the rock-
ing frame upon pivots which are relatively 55
adjustable laterally, that is, forwardly and
backwardly upon the machine, so that an
end of the universal bar may be swung hori-
zontally either forwardly or backwardly, as
required, thereby bringing it into the re- 60
quired parallelism.

The invention also comprises an improved
mounting for a dog-rocker stop, which is
movable to a position such as to permit an
amplified movement of the rocker and uni- 65
versal bar to facilitate the insertion and re-
moval of the type-bars.

Other features and advantages will here-
inafter appear.

In the accompanying drawings, 70
Figure 1 is a central sectional side view
of an Underwood typewriting machine, illus-
trating the present improvements.

Figure 2 shows part of the devices seen at
Figure 1, and illustrates the method of re- 75
moving a type-bar from the machine.

Figure 3 is an enlarged detail of a conical
pivot and a fitting therefor in the arm of a
universal bar frame.

Figure 4 illustrates details of a stop-lever 80
which is movable to permit the operation
seen in Figure 2.

Figure 5 is an enlarged perspective view
of a conical pivot for the rocking frame
which carries the universal bar, showing the 85
arbor or mount for said pivot and its ad-
justing head and locking pin.

Figure 6 is a rear view of the escapement
mechanism.

Figure 7 is a sectional view, taken about 90
centrally of Figure 6.

Keys 20 depress levers 21 to operate bell-
cranks 22 to swing type-bars 23 up against
the front of a platen 24, as is common in the
Underwood machine; said platen being 95
mounted upon a carriage 25 running on
tracks 26, 27. A carriage rack 28 meshes
with a pinion 29 that is connected to an es-
capement wheel 30, for controlling the let-
ter-feeding movements of the carriage, the 100
latter being driven by a spring barrel 31
under control of the escapement wheel. The
movements of the wheel are controlled by a
rocker 32, having a rigid dog 33 and a step-
ping dog 34, the latter normally meshing 105
with the wheel; and movements are imparted

to the dog rocker by a striker 35, which is carried by a frame 36, the latter comprising a universal bar 37, operable by heels 38 upon the type-bars. The universal bar 37 is concentric with the wire 39, upon which the type-bars are usually pivoted.

At the depression of any key, its bell-crank 22 is operated, and the type-bar 23 swung up to the printing point, pressing back the universal bar 37 and frame 36, and by means of the striker 35 pressing the dog rocker back, so that the stepping dog 34 thereon escapes from the wheel 30, and the rigid detent dog 33 is carried into mesh with the wheel. The dog 34 is swung by a spring 40 to a point opposite the next notch in the escapement wheel 30. Upon relief of the key from pressure, it is returned by a spring 41; the type-bar returns to normal position, and the universal bar is returned by a spring 42. The spring 40 operates also to return the dog rocker to the normal Figure 1 position.

One of the features of invention resides in the mounting of the universal bar frame 36. This frame is necessarily light, because it has to be moved quickly by its returning spring 42, and is therefore weak, but it must move accurately, since it not only operates the letter-feeding mechanism, but also vibrates the ribbon to cover the printing point at each type stroke. This ribbon movement must be accurate, especially where a bichrome ribbon is used, in which the type striking field is extremely narrow, and in which under-throw and overthrow must be practically eliminated. The ribbon vibrator comprises a lever 43 engaged by an actuator 44, which is mounted upon the universal bar frame 36. The lever is connected to vibrate a ribbon carrier 45, as usual in the Underwood typewriter.

This universal bar frame 36 has at its rear ends opposite arms 46, 47, which are pivoted upon upright guide arms 48, 49; the frame 36 being guided at its front end in the usual manner by a tongue 50 working in the type-bar segment 51. These arms rise from a rock shaft 52, which is pivoted between uprights 53, 54, forming part of a general framework for the escapement mechanism.

In order for the light and weak universal bar frame 36 to actuate the letter-feed dogs and the ribbon-vibrating mechanism with the required nicety, it is important that the front edge of the universal bar 37 should lie in a plane parallel with the plane of the curved wire 39 upon which the type-bars are fulcrumed, and which is about concentric with the printing point. This is desired so that the universal bar will be given equal strokes by all the type-bars. In order to secure this parallelism, it has been the practice to bend the universal bar frame 36. This, however, has demanded high skill,

and has been slow and expensive in manufacturing and repairing or overhauling the same, particularly since this frame is confined at the middle part of the machine, where it is surrounded by various other parts and hence inaccessible and inconvenient for bending in the required manner.

The desired alignment of the universal bar 37 is obtained by providing for bodily adjustment of the rocking guide frame 48, 49, 52. To this end, the rocking frame is mounted upon pivots 55, 56, which are relatively adjustable laterally in a manner to displace one side of the rocking frame either forwardly or backwardly of the machine. The pivot 55 is in the form of a screw having a conical point, which fits in a bearing in one end of the shaft 52 the arbor or mount 56 having a conical point 57, which fits in a similar bearing in the opposite end of the rock shaft 52. The pivot 55 may be stationary, except that it may be shifted endwise to adjust or take up play of the rock shaft 52; but the pivot point 57 is adjustable forwardly and backwardly; the arbor 56 being for this purpose mounted eccentrically of the pivot point 57. The pivot 57 should be at its topmost position, as in Figure 7, and may be secured against rotative displacement by a locking pin 58, which may enter any of several notches 59 in a head 60 provided upon the arbor or shaft 56; said pin fixed at 61 in the casting 54. If, however, the universal bar 37 should be found to operate differently at one end from the other, this difficulty can be corrected, by first taking out the arbor or shaft 56 and turning it so as to shift the pivot 57 either forwardly or backwardly, and then restoring said arbor, thereby displacing this end of the rocking frame 48, 49, 52, and hence swinging the frame 36 and universal bar 37 horizontally until the front or active edge of said universal bar is exactly parallel with the plane of the pivot wire 39; the pin 58 now occupying another notch 59, to re-lock the arbor 56 against displacement. A set screw 62 may also be provided for the pivot or eccentric 56, to hold it where adjusted endwise in connection with the opposite pivot 55. It thus becomes practicable and simple to secure accuracy of movement not only of the ribbon-vibrator, but also of the feed-dogs, enabling a closer timing of the operation of said dogs to be made, especially at the return strokes of the type-bars from the platen, with a view of rendering the machine speedier and more accurate.

The arms 48, 49 may be provided with gudgeons or pivots, one of which, 63, is threaded so as to be adjustable, and is secured by a set screw 64 and cone-pointed at 65, Figure 3, to fit in a conical hole 66, made in the arm 46. The screw 64 may

be loosened, and the pivot 63 screwed out to take up the shake, and the screw 64 then tightened. In arm 49 is forced a companion pivot or gudgeon 63^a, to fit in a conical hole made in arm 47. This construction and mounting of the frame 36 and the frame 48, 49, 52 gives lightness and therefore conduces to speed of action, and permits the pivot shaft to be dispensed with, which usually extends from arm 46 to arm 47 and renders the feeding dogs inaccessible.

The detent dog 33 and the stepping dog 34 are carried upon the rocker 32. Said rocker may be journaled upon adjustable pivots 67 secured by set screws 68. The universal bar frame striker 35 engages the end of a screw 69, which is threaded into the upper portion of the dog rocker 32; the screw being adjustable to secure fine variations in the timing of the rocker action. The dog rocker is returned by the spring 40 to normal position, the lower end of the rocker engaging the head of a stop screw 70 threaded into the framework. At its lower end, the rocker also carries an adjustable screw 71, which strikes against a stop 72 to limit the initial movement of the rocker. This stop 72 is pivoted upon a screw 73, and has a handle 74, whereby it may be swung out of the path of the screw 71, to permit additional movement of the dog rocker and universal bar frame 36 when it is desired to detach any type-bar from the machine, Figure 2, said stop 72 being returned by a spring 75 against a stop pin 75^a. The stepping movement of the dog 34 is limited by a cone-headed adjustable screw 76 shown as carried by the dog-rocker 32.

Variations may be resorted to within the scope of the invention, and portions of the improvements may be used without others.

Having thus described my invention, I claim:

1. In a typewriting machine, the combination with a set of type-bars pivoted in an arc, of a curved universal bar in the paths of the type-bars for operation thereby, a frame of which said universal bar forms a part, a ribbon-vibrator operated by said universal bar frame, a rocking frame constituting a support for said universal bar frame, pivots for said rocking frame, and means for effecting relative lateral adjustment of said pivots to bring the edge of the universal bar into parallelism with the plane of the arc of the type-bar pivots.

2. In a typewriting machine, the combination with a set of type-bars pivoted in an arc, of a curved universal bar in the paths of the type-bars for operation thereby, a frame of which said universal bar forms a part, a rocking frame constituting a support for said universal bar frame, and means movable for bringing the edge of said universal bar

into parallelism with the arc of said type-bar pivots.

3. In a typewriting machine, the combination with a set of type-bars pivoted in an arc, of a curved universal bar, a frame of which said universal bar forms a part, a rocking frame constituting a support for said universal bar frame, and pivots for said rocking frame, one of said pivots having an eccentric mounting whereby said rocking frame and universal bar frame may be swung about the other of said pivots. 75

4. In a typewriting machine, the combination with a set of type-bars pivoted in an arc, of a curved universal bar in the paths of the type-bars for operation thereby, a frame of which said universal bar forms a part, a rocking frame constituting a support for said universal bar frame, pivots for said rocking frame, and means for effecting relative lateral adjustment of said pivots to bring the edge of the universal bar into parallelism with the plane of the arc of the type-bar pivots, said rocking frame pivots being also relatively adjustable endwise. 80

5. In a typewriting machine, the combination with a set of type-bars pivoted in an arc, of a curved universal bar, a frame of which said universal bar forms a part, a rocking frame constituting a support for said universal bar frame, pivots for said rocking frame, one of said pivots having an eccentric mounting whereby said rocking frame and universal bar frame may be swung about the other of said pivots, said mounting having a disk provided with notches, and a pin insertable in any of the notches to lock the mounting against rotation. 95

6. In combination, a universal bar frame supported at one end, said universal bar frame having at its other end two spaced arms provided with depressions to receive pivot points, a rocker having two arms, each of which has its free end adjacent one of the arms of the universal bar frame, a pivot point fixed in one rocker-arm and engaging in the depression in the adjacent frame-arm, and another pivot point threaded in the other rocker-arm in position to engage in the depression in the adjacent frame-arm, whereby any excessive play between the universal bar frame and the rocker may be taken up. 105

7. The combination with a set of detachable type-bars, of a carriage escapement mechanism, comprising a universal bar engageable by type-bars of said set, a dog-rocker operable by said universal bar, a rocker-bracket having parallel arms in which said dog-rocker is pivoted and a U-shaped connector for said arms extending to one side of the plane of said arms so as to permit a sufficient movement of said dog-rocker, a stop for arresting said dog-rocker, 120

125

130

and a substantially horizontal lever carrying said stop and pivoted on the face of said connector, said lever having an arch extending over the adjacent side of said connector 5 and a finger-piece at the outer end of said arch extending laterally beyond the adjacent arm of the rocker-bracket, movement of said finger-piece from its normal position being effective to displace said stop and permit additional movement of the dog-rocker and 10 universal bar to permit detachment of a type-bar.

8. In a typewriting machine, the combination with a universal bar, of a rocking frame connected to the universal bar, and means for effecting relative adjustment of 15 the ends of said universal bar, comprising a pivot bearing for said frame mounted for adjustment transversely to the axis of the pivot, means for securing said bearing where 20

adjusted, and locking means for preserving the adjustment.

9. In a typewriting machine, the combination with a series of key-actuated members and an escapement-operating universal bar in the paths of said members for actuation thereby, of a supporting rocker connected to the universal bar and having opposite conical bearings, cone pivots for said bearings, each pivot being adjustable in an axial 25 direction independently of the other, and means whereby an adjustment of one of said pivots in a direction transversely to its axis may be effected independently of the other pivot to adjust the universal bar relatively 30 to the key-actuated members.

WILLIAM F. HELMOND.
